BRAKE HANGER BRACKET

Alfred H. Oelkers, Chicago, Ill., assignor to
American Steel Foundries, Chicago, Ill., a cor-
poration of New Jersey

Application October 22, 1938, Serial No. 236,392

16 Claims. (Cl. 188—209)

My invention relates to brake hangers for railway car trucks and supporting means therefor.

It is a well known fact that in railway equipment all parts are subjected to severe vibrations and this is particularly true of parts that are suspended from other members as, for example, brake hangers. Frequently the wear of parts so supported, due to vibration thereof, is determinative of their useful life rather than the actual application of such parts to the purpose intended; in other words, if such parts could be so supported that the wear due to vibration could be avoided, the period of their useful life could be greatly extended. One such part is the common loop-type brake hanger which has long been supported from a well known type of bracket having a jaw at the end thereof within which the top member of said hanger is supported. Numerous types of wear plates for such jaws have been devised and various means of resiliently supporting the hanger therein have been tried.

An object of my invention is to devise an arrangement of a loop-type brake hanger supported from a jaw-type bracket which will dispense with all wear on the hanger at the point of support.

My invention comprehends furthermore an arrangement which will permit the ready replacement of the resilient means in which the hanger is supported whenever the resilient quality of such means shall have deteriorated to the point where it is no longer useful.

My invention further contemplates a resilient means of supporting such a brake hanger so that at the point of support said hanger will be free of engagement with any other metal part, thus preventing frictional wear thereof.

In my novel arrangement the hanger is supported from resilient material and said resilient material is placed under sufficient compression so that all the parts are tightly fitted against each other, thus reducing to a minimum destructive vibration and preventing altogether the noise and chatter which commonly results as play develops between engaging metal parts.

These and various other objects will be more apparent from the following description of several modifications of my invention and from the appended claims.

Figure 1 is a top plan view of a brake hanger bracket incorporating one embodiment of my invention; Figure 2 is a side elevation thereof; and Figure 3 an end elevation;

Figure 4 is a sectional view through the structure shown in Figures 1 to 3, the section being taken substantially in the vertical plane indicated by the line 4—4 of Figure 3;

Figure 5 is an end view, half in section, of the

rubber bushing embodied in the structure shown in Figures 1 to 4, the section being taken substantially in the plane indicated by the line 5—5 of Figure 6, and Figure 6 is a side elevation thereof, partly in section, the section being taken substantially in the plane indicated by the line 6—6 of Figure 5;

Figure 7 is an end elevation of the retainer member, and Figure 8 is a top plan view thereof, half in section, the section being taken in the plane bisecting the retainer and substantially as indicated by the line 8—8 of Figure 7;

Figure 9 is a top plan view of a brake hanger bracket incorporating a second embodiment of my invention;

Figure 10 is a side elevation of the structure shown in Figure 9, and Figure 11 is an end view thereof;

Figure 12 is a sectional view through the structure shown in Figures 9 to 11, the section being taken substantially in the plane indicated by the line 12—12 of Figure 11;

Figure 13 is an end view, half in section, of the rubber bushing associated with that embodiment of my invention shown in Figures 9 to 12, inclusive, the section being taken substantially in the plane indicated by the line 13—13 of Figure 14;

Figure 14 is an elevational view, partly in section, of the bushing shown in Figure 13, the section being taken substantially in the plane indicated by the line 14—14 of Figure 13;

Figure 15 is an end view of the retainer associated with the last mentioned embodiment of my invention, and Figure 16 is a side elevation thereof;

Figure 17 is a top plan view of a structure incorporating a further embodiment of my invention; Figure 18 is a side elevation thereof; and Figure 19 is an end view thereof, partly in section, the section being taken substantially in the transverse vertical plane as indicated by the line 19—19 of Figure 18; and

Figure 20 is a sectional view of the structure shown in Figures 17 to 19, the section being taken in a vertical plane and substantially as indicated by the line 20—20 of Figure 19.

Describing my invention in greater detail and referring more particularly to the modification shown in Figures 1 to 8, the truck frame member 2 has the integrally formed brake hanger bracket 4 reinforced by the vertically arranged central rib 5 and terminating in a jaw-like structure having the top and bottom flaring walls 6 and 8 forming therebetween the opening 9 recessed at the rear as indicated at 10, said recess being defined further by the lateral walls 11 and 13. Received within the jaw opening 9 is the horizontal top member 12 of my novel brake hanger 14, said brake hanger being of the loop-

type having the side members 16, 16. Encasing the said top member 12 is the resilient bushing 18 of a form more particularly described hereafter. In abutment against one side of said bushing as at 20 (Figure 4) is my novel retaining plate 22 of the form shown in detail in Figures 7 and 8, said retaining plate having the central cylindrical portion 24 with the generally vertically arranged opening 26 receiving the retaining key or cotter 28, said cotter also extending through the aligned openings 30 and 32 (Figure 4) formed in the before mentioned top and bottom walls 6 and 8. The cotter 28 has a tapering end of usual form as best seen at 29 (Figure 2), so arranged to accommodate its forcible insertion into position against the retaining plate 22, thus compressing somewhat the bushing 18. The bushing 18 is positioned at its extremities against the complementary curved forward edges of the lateral walls 11 and 13 as best seen at 34 (Figures 2 and 4), said walls thus providing means against which the bushing may seat.

The bushing 18 is shown in detail in Figures 5 and 6 wherein it may be observed that it is of generally cylindrical form having the central opening 36 and the slot 38 at one side thereof, said slot being formed to permit the insertion of the top member 12 of the brake hanger, said member being inserted by distorting the rubber bushing sufficiently to force said member therein. Centrally formed at the slotted side of said bushing is the arcuate channel 40 against which may be seated as at 20 the inner face of the cylindrical portion 24 on the retaining plate 22.

The form in detail of the retaining plate 22 is shown in Figures 7 and 8. It will be noted that the plate is of somewhat arcuate form as best seen in the end view of Figure 7 having the central channel indicated at 42 forming seating means for the full length of the bushing 18 at the slotted side thereof. The said channel 42 is broken centrally thereof by the before mentioned cylindrical portion 24 which forms a key way for the cotter 28 and the inner wall of the cylindrical portion 24 is received within the channel 40 on the bushing 18 as already described.

In this embodiment of my invention it will be observed that I have provided a novel form of securing means for a loop-type brake hanger wherein all the parts are tightly fitted and no free play is permitted therebetween.

In the embodiment of my invention shown in Figures 9 to 16, inclusive, the truck member 44 has the integrally formed brake hanger bracket 46 reinforced by the centrally formed top rib 48, said bracket terminating in the jaw-like structure substantially identical to the embodiment previously described and having the flaring top wall 50 and the flaring bottom wall 52 forming therebetween the jaw opening 54 (Figure 4) having at its rear the cavity 56 further defined by the lateral walls 58 and 60, the forward edges of said lateral walls 58 and 60 (Figure 9) having an arcuate configuration (Figures 10 and 12). Received in said jaw opening 54 is the loop-type brake hanger 62, the top member 64 thereof being encased in the rubber bushing 66 of novel form more particularly described hereafter. The back or rear wall of said bushing is of generally cylindrical form and at its extremities seats as at 68, 68 against the arcuate forward edges of the lateral walls 58 and 60. The outwardly directed face of the bushing is of the configuration best seen in Figure 13, and of com-

plementary form with the retaining plate 70 which is seated there-against, said retaining plate forming a means of abutment for the cotter pin 72, said cotter pin being received in the aligned openings 74 and 76 formed respectively in the top and bottom walls 50 and 52.

The form and detail of the bushing 66 is shown in Figures 13 and 14. It will be noted that the bushing is of generally cylindrical form with the central opening 78 within which the top member 10 of the brake hanger may be seated by distorting the bushing, said distortion being permitted by the slot 80 centrally formed in the outwardly directed wall of said bushing. The configuration of said outwardly directed wall is of irregular 15 form as seen in Figure 13 and complementary to the form of the retaining plate 70 against which it is seated. Said bushing has the centrally formed vertical channel 82 receiving the channel portion 84 of the retaining plate 70, said channel 20 portion being formed to accommodate the cotter key 72.

The detail of the retaining plate 70 is shown in Figures 15 and 16. It will be noted that the configuration is complementary in form to that of the 25 outer face of the bushing 66. The central channel portion 84 is flared as indicated at 86, 86 (Figure 15) to accommodate insertion of the cotter 72, the said flaring structure permitting the tapering end of the cotter 72 to be inserted through 30 the opening in the top wall of the jaw and to be forced into the central channel 84 of the retaining plate thereby compressing somewhat, by this operation, the rubber bushing 66 so that all of the parts will be in tight engagement with each 35 other.

In this second embodiment of my invention it will be noted likewise that all the parts are firmly seated against each other so as to eliminate all free play therebetween.

In the embodiment shown in Figures 17 to 20, inclusive, the truck frame 88 has the integrally formed brake hanger bracket 90 with the up-standing reinforcing rib 92, said brake hanger bracket terminating in a novel form of jaw 94 45 designed particularly for reception of my novel form of brake hanger 96. The said jaw 94 is of hook-like form as viewed in the side elevation, the rear wall thereof being of generally cylindrical formation and the top wall thereof terminating at 98 where the juncture is formed with the before mentioned reinforcing top rib 92. The said cylindrical rear wall presents an inner face complementary in form to the side wall of the 55 bushing 100, said bushing encasing the top member 102 of the brake hanger 96. Inwardly of the jaw 94 the flange 92 has an opening 104 receiving the securing bolt 106, the opposite end of said securing bolt being received in the aligned opening 60, 108 formed in the retaining plate 110, securing means for said bolt being in the form of the threaded nut 112 which may be drawn up tight against the nut locking angle plate 114 which is flanged over as at 116 to abut the end of the retaining plate 110 and may be flanged over at the opposite end as at 118 to lock said nut in place.

The bottom wall of the jaw 94 is horizontally extended as at 120 and provided with the rectangular slot 122 for reception of the tongue 124, 70, said tongue 124 being inserted in the slot after the bushed brake hanger has been applied in the brake hanger 96 and thereafter the securing bolt 106 being applied and the nut thereof drawn up tight to retain the parts in place.

In this modification the bushing 100 is sleeved upon the top member of the hanger although, if desired, it may be formed with a slot as in previous modifications. In this modification, as 5 shown, the bushing 100 is unslotted and is a solid cylinder of rubber composition material, the inner wall of which may be seated as at 126 (Figure 20) against the inner wall of the jaw 94 being complementary therewith and the front wall 10 thereof may be seated as at 128 against the central portion of the retaining plate 110, said central portion being of arcuate form as at 130 with an inner face complementary to said bushing.

To those skilled in the art it will be readily apparent that in the first two modifications described I have adapted my novel brake hanger and retaining plate to a well known type of A. A. R. standard brake hanger jaw. In the last modification described, however, I have designed 20 a form of jaw and retaining plate therefor most efficient for my novel form of brake hanger.

It is to be understood that I do not wish to be limited by the exact embodiments of the device shown which are merely by way of illustration 25 and not limitation as various and other forms of the device will, of course, be apparent to those skilled in the art without departing from the spirit of the invention or the scope of the claims.

I claim:

30. 1. In a railway car truck, a frame member, a brake hanger bracket integrally formed therewith and having a jaw end with top and bottom walls and lateral walls defining a cavity at the rear of said jaw, said lateral walls terminating rearwardly of said top and bottom walls in edges of arcuate form, a loop-type brake hanger having a top member seated in said jaw, a resilient bushing sleeved upon said top member and seated against said edges, a retaining plate having a rear wall complementary in form to the front wall of said bushing and in abutment thereagainst, and means for urging said retaining plate against said bushing and maintaining said plate in position, said means comprising aligned openings in said top and bottom walls, a vertical channel in said retaining plate aligned with said openings, and a key with tapered end extending through said openings and seated in said channel.
35. 2. In a railway car truck, a frame member, a brake hanger bracket integrally formed therewith and having a jaw end with top and bottom walls and lateral walls defining a cavity at the rear of said jaw, said lateral walls terminating rearwardly of said top and bottom walls in edges of arcuate form, a loop-type brake hanger having a top member seated in said jaw, a resilient bushing sleeved upon said top member and seated against said edges, a retaining plate having a rear wall complementary in form to the front wall of said bushing and in abutment thereagainst, and means for forcing said retaining plate against said bushing, said means comprising aligned openings in said top and bottom walls, a vertical channel in said retaining plate aligned with said openings, and a key with tapered end extending through said openings and seated in said channel, said channel having flaring ends whereby the tapered end of said key 40 may be forcibly inserted into said channel thus compressing said bushing.
40. 3. In a railway car truck, a frame member, an integrally formed bracket having a brake hanger jaw with lateral walls and flaring top and bottom walls, said lateral walls having forward edges of arcuate form terminating rearwardly of said top and bottom walls, a brake hanger having its top member seated in said jaw, a resilient bushing sleeved upon said top member and in abutment with said edges, said bushing being of complementary form with said flaring walls and in abutment therewith, a retaining plate complementary in form to the front wall of said bushing and comprising a vertical central channel, 45 and securing means extending through said top and bottom walls and seated in said channel.
45. 4. In a railway car truck, a frame member, an integrally formed bracket having a brake hanger jaw with flaring top and bottom walls and lateral walls, said lateral walls having forward edges of arcuate form terminating rearwardly of said top and bottom walls, a brake hanger having its top member seated in said jaw, a resilient bushing sleeved upon said top member and in abutment with said edges, said bushing being of complementary form with said flaring walls and in abutment therewith, a retaining plate complementary in form to the front wall of said bushing and comprising a vertical central channel, 50 and securing means extending through said top and bottom walls and seated in said channel.
50. 5. In a railway car truck, a frame member, having a bracket with a brake hanger jaw, said jaw having top and bottom walls and lateral walls with arcuate front edges terminating rearwardly of said top and bottom walls, a brake hanger having a top member extending through said jaw, a resilient bushing sleeved upon said top member and having end portions of complementary form with said edges and seated thereagainst, and means for retaining said bushing in position under compression, said retaining means comprising a plate having a central cylindrical portion with an orifice therethrough, 55 openings in said top and bottom walls aligned with said central orifice, and a key extending through said orifice and openings.
55. 6. In a railway car, a frame member having an integral brake hanger bracket with a brake hanger jaw formed thereon, said jaw having side walls of arcuate formation at their outer edges, a loop-type brake hanger having a top member seated in said jaw, a resilient bushing sleeved upon said top member and abutting said side walls, a retaining plate of complementary form with the front wall of said bushing and seated thereagainst, said retaining plate having a central vertically arranged cylindrical portion with an orifice therethrough, 60
60. 7. In a railway car, a frame member having an integral brake hanger bracket with a brake hanger jaw formed thereon, said jaw having side walls of arcuate formation at their outer edges, a loop-type brake hanger having a top member seated in said jaw, a resilient bushing sleeved upon said top member and abutting said side walls, a retaining plate of complementary form with the front wall of said bushing and seated thereagainst, said retaining plate having a central vertically arranged cylindrical portion with an orifice therethrough, 65
65. 8. In a railway car truck, a frame member, a brake hanger bracket integrally formed thereon, said jaw having side walls of arcuate formation at their outer edges, a loop-type brake hanger having a top member seated in said jaw, a resilient bushing sleeved upon said top member and abutting said side walls, a retaining plate of complementary form with the front wall of said bushing and seated thereagainst, said retaining plate having a central vertically arranged cylindrical portion with an orifice therethrough, 70
70. 9. In a railway car truck, a frame member, a brake hanger bracket integrally formed thereon, said jaw having side walls of arcuate formation at their outer edges, a loop-type brake hanger having a top member seated in said jaw, a resilient bushing sleeved upon said top member and abutting said side walls, a retaining plate of complementary form with the front wall of said bushing and seated thereagainst, said retaining plate having a central vertically arranged cylindrical portion with an orifice therethrough, 75

- and key means extending through said jaw and received in said orifice.
8. In a railway car, a frame member having an integral brake hanger bracket with a brake hanger jaw formed thereon, said jaw having side walls of arcuate formation at their outer edges, a loop-type brake hanger having a top member seated in said jaw, a resilient bushing sleeved upon said top member and abutting said side walls, a retaining plate of complementary form with the front wall of said bushing and seated there-against, a central channel formed in said retaining plate, and retaining means extending through said jaw and seated in said central channel, said retaining means serving to compress said bushing between said side walls and said plate.
9. In a railway car, a frame member having an integral brake hanger bracket with a brake hanger jaw formed thereon, said jaw having side walls of arcuate formation at their outer edges, a loop-type brake hanger having a top member seated in said jaw, a resilient bushing sleeved upon said top member and abutting said side walls, a retaining plate of complementary form with the front wall of said bushing and seated there-against, said retaining plate having a vertically arranged central channel, and key means extending through said jaw and seated in said channel against said retaining plate, the insertion of said key means serving to compress said bushing between the arcuate edges of said side walls and said plate whereby said hanger, said plate and said key means are secured against vibration.
10. In a railway car, a frame member having an integral brake hanger bracket with a brake hanger jaw formed thereon, said jaw having side walls of arcuate formation at their outer edges, a loop-type brake hanger having a top member seated in said jaw, a resilient bushing sleeved upon said top member and abutting said side walls, a retaining plate of complementary form with the front wall of said bushing and seated thereagainst, and retaining means extending through said jaw and seated against said retaining plate, said retaining means comprising a key with tapered end extending through aligned openings in the top and bottom walls of said jaw and serving to compress said bushing between the arcuate outer edges of said side walls and said retaining means whereby said parts are secured against vibration.
11. In a railway car truck, a frame member having a bracket with a brake hanger jaw, said jaw having top and bottom walls and lateral walls with arcuate front edges terminating rearwardly of said top and bottom walls, a brake hanger having a top member extending through said jaw, a resilient bushing sleeved upon said top member and having end portions of complementary form with said edges and seated thereagainst, and means for retaining said bushing in position under compression, said retaining means comprising a pin extending through said top and bottom walls and a retaining plate between said pin and said bushing, said pin serving to urge said plate against said bushing and said bushing against said edges whereby said hanger and said retaining means are restrained against vibration.
12. In a railway car truck, a frame member having an integral bracket with a brake hanger jaw, a brake hanger with a top member seated in said jaw, a resilient bushing sleeved on said top member in abutment with portions of said jaw,
- a retaining plate having channels therein disposed approximately at right angles to each other with one of said channels seated against said bushing, and securing means for said plate in abutment therewith along the other of said channels, said securing means comprising a pin with tapered end extending through aligned openings in top and bottom walls of said jaw, said tapered end affording means of comprising said plate against said resilient bushing and urging said resilient bushing tightly into said jaw whereby said hanger and said securing means are restrained against vibration.
13. In a railway car truck, a frame member having a bracket with a brake hanger jaw, a brake hanger having a top member seated in said jaw, a resilient bushing sleeved upon said top member in abutment with a portion of said jaw, a retainer plate having channels angularly disposed with respect to each other, one of said channels having abutment against said sleeve, and securing means engaging said plate along the other of said channels, said securing means comprising a key with tapered end receivable in aligned openings in top and bottom walls of said jaw, said tapered end affording means of compressing said bushing between said plate and said portion of said jaw.
14. In a railway truck, a frame having a bracket with a brake hanger jaw, a brake hanger having a top member seated in said jaw, a resilient bushing sleeved upon said top member, a retaining member having channels angularly disposed with respect to each other with one of said channels engaging said bushing, and securing means in abutment with said plate along the other of said channels, said securing means comprising a pin with tapered end receivable in aligned openings in top and bottom walls of said jaw and serving upon application as means of compressing said bushing between said jaw and said plate to prevent vibration and frictional wear of said hanger and said securing means.
15. In a railway truck, a frame having a bracket with a brake hanger jaw, a brake hanger having a top member seated in said jaw, a resilient bushing sleeved upon said top member, a retainer member having angularly disposed channels one of which forms a seat for said bushing, and securing means extending through the walls of said jaw and in abutment with the other of said channels, said securing means comprising a pin with tapered end affording in application a means of urging said retainer member against said bushing and said bushing tightly within said jaw whereby said hanger, said retainer member and said pin are secured against vibration.
16. In a railway car truck, a frame having a bracket with a brake hanger jaw, a brake hanger having a top member seated in said jaw, a resilient bushing sleeved thereon, a retainer plate for said bushing comprising a channel in abutment therewith, and an orifice angularly disposed with respect thereto, and securing means extending through said orifice and through said jaw to retain said parts in assembly, said securing means comprising a pin with tapered end affording in application means of compressing said resilient bushing between said plate and said jaw whereby said hanger is supported in said jaw without frictional vibration against said jaw or said securing means.

ALFRED H. OELKERS.

CERTIFICATE OF CORRECTION.

Patent No. 2,232,468.

February 18, 1941.

ALFRED H. OELKERS.

It is hereby certified that error appears in the printed specification of the above numbered patent requiring correction as follows: Page 4, second column, line 9, claim 12, for the word "comprising" read --compressing--; and that the said Letters Patent should be read with this correction therein that the same may conform to the record of the case in the Patent Office.

Signed and sealed this 21st day of October, A. D. 1941.

Henry Van Arsdale,
Acting Commissioner of Patents.
